SHOULDER MOUNTED RADIO TRANSCEIVER

Charles Neumiller, 14205 Arnold Drive, Glen Ellen, Calif.

Filed Nov. 1, 1961, Ser. No. 67,328

Term of patent 14 years

(Cl. D26—14)

FIG. 3

FIG. 4

FIG. 5

FIG. 6

FIG. 1 is a view in perspective of a shoulder mounted radio transceiver showing my new design;

FIG. 2 is a fragmentary view in rear elevation of the same;

FIG. 3 is a fragmentary view in side elevation of the same;

FIG. 4 is a fragmentary view in front elevation of the same;

FIG. 5 is a fragmentary view in side elevation of the same taken from the side opposite to that shown in FIG. 3;

FIG. 6 is a fragmentary top plan view of the same.

A portion of the antenna and the attachment cord have

been omitted from certain of the figures for convenience in illustration. The perforations in the microphone-loud-speaker grill are continuous thereover.

1 claim:

The ornamental design for a shoulder mounted radio transceiver, substantially as shown and described.
